(57) CLAIM

The ornamental design for a decorative pattern for a pocket, as shown and described.

DESCRIPTION

FIG. 1 is a front elevational view of a decorative pattern for a pocket showing my design;

FIG. 2 is a front view thereof, shown in the environment of a pair of pants;

FIG. 3 is another front elevational view thereof; and,

FIG. 4 is another front view thereof, shown in the environment of a pair of pants.

The broken lines in FIGS. 1-4 represent environmental structure only and form no part of the claimed design.
